UNITED STATES PATENT OFFICE.

BUFORD J. STEEN, OF GOOSE CREEK, TEXAS.

ELEVATOR.

1,328,602.

Specification of Letters Patent. Patented Jan. 20, 1920.

Application filed February 24, 1919. Serial No. 278,802.

To all whom it may concern:

Be it known that BUFORD J. STEEN, a citizen of the United States, residing at Goose Creek, in the county of Harris and 5 State of Texas, has invented certain new and useful Improvements in Elevators, of which the following is a specification.

This invention relates to new and useful improvements in an elevator, which has been 10 specially designed for the purpose of lifting pipe and other similar objects. In well drilling, particularly in the drilling of oil wells, pipe must be let down into and withdrawn from the bore, in connection with the 15 drilling operations, and in so handling the pipe, an elevator is first clamped around said pipe underneath one of the collars, connecting the joints thereof and a cable is then attached to the elevator bail, through 20 which the pipe is lifted out of and suspended into, the bore, said cable being operated usually by means of a drum, not shown, or through other suitable means, provided for the purpose. It is the object 25 of this invention to provide an elevator of simple construction, and which may be readily applied to and released from the pipe to be handled.

Another object of the invention resides 30 in the provision of an elevator of the character described, which may be easily attached to the pipe, and as readily disengaged therefrom.

A further feature of the invention resides 35 in the provision of an elevator of the character described, which may be cheaply and easily constructed, and easily kept in repair.

With the above and other objects in view, the invention has particular relation to certain 40 novel features of construction, operation and arrangement of parts, an example of which is given in this specification and illustrated in the accompanying drawings, wherein:

45 Figure 1, is a plan view of the elevator attached to a pipe.

Fig. 2, is a side elevation thereof.

Fig. 3, is a side elevation taken at right angles to the view shown in Fig. 2, and

50 Fig. 4, is a fragmentary side view of the locking arm employed.

Referring now more particularly to the drawings, wherein like numerals of refer-

ence designate similar parts in each of the figures, the numeral 1, refers to an arcuate member, formed to conform to and fit around the pipe 2, underneath the collar 3 thereof. This member has the oppositely disposed eyes 4, 4, secured thereto, to which the bail 5 is attached. To one end of the arcuate member 1, the arm 6 is hinged, and the free end of this arm has the reduced neck 7, and the head 8. When the arm is in closed position, the neck 7 fits into the slot 9, cut in the other end of the arcuate member 1, 60 the head 8 resting in the notch 10, of said end, so as to be flush therewith. The head 8 has the transverse notch 11, in the outer end thereof, in which the spring dog 12 is adapted to engage, to hold the arm 6 in 65 locked position. Integral with the arm 6, there is a finger 13, curved to conform to the contour of the pipe, and which rests in a correspondingly shaped recess 14, of the member 1, when the elevator is applied to 70 the pipe. As shown in the figures, the elevator is applied to the pipe 2, underneath the collar 3, so that when it is pulled upwardly, it will engage with said collar and lift the string of pipe. If it now be desired 75 to remove the elevator, the spring dog 12 may be manually disengaged, and the member 1 moved laterally, relative to the pipe, causing the pipe to engage with the arm 6, and move it into the position indicated in 80 dotted lines in Fig. 1. In applying the elevator to the pipe, the finger 13 will first engage against the pipe and be swung around thereby and seated in the recess 14, 85 operating to swing the arm 6 into the position shown in full lines in Fig. 1, the neck 7 fitting into the slot 10, and the spring dog 12 engaging in the notch 11, to lock the arm 6 in position underneath the collar 3, where 90 it will be securely held until again manually released.

What I claim is:

An elevator, including an arcuate member, conforming in contour to and adapted to be fitted around a pipe, a securing arm 100 pivoted at one end to one end of said member, the other end of said member and arm being formed to interengage providing means whereby the arm may be locked in position to hold said arcuate member, 105 against detachment from the pipe, and an

actuating finger carried by said arm, and adapted to be actuated by the pipe, when the elevator is applied thereto to swing the arm into interlocking engagement with said 5 member, and to hold said arm in locked position when the elevator is secured to the pipe.

In testimony whereof I have signed my name to this specification in the presence of two subscribing witnesses.

BUFORD J. STEEN.
